Filed Jan. 2, 1962, Ser. No. 68,131

Term of patent 14 years

(Cl. D58—17)

FIG. 1.

FIG. 3.

FIG. 2.

FIG. 6.

FIG. 4.

FIG. 5.

FIG. 1 is a top plan view of a combined pressurized can and dispensing nozzle kit, showing our new design; FIG. 2 is a side elevational view thereof;

FIG. 3 is a bottom perspective view of the cover;

FIG. 4 is a bottom perspective view of the flower nail;

FIG. 5 is a bottom plan view of the dispensing nozzle cluster which surrounds the dispensing valve on the top of the can; and

FIG. 6 is a longitudinal sectional view of one of the dispensing nozzles.

The essential features of our design reside in the portions shown in full lines and more particularly in the nozzle cluster as shown in FIGS. 2 and 5.

We claim:

The ornamental design for a combined pressurized can

and dispensing nozzle kit, substantially as shown and described.
